HOLDER FOR GOLF TEES AND BALL MARKERS

Louise O. Hyler, Elmhurst, Ill.
(R.R. 2, Marcelline, Mo. 64658)

Filed June 15, 1965, Ser. No. 85,745

Term of patent 7 years

(Cl. D34—5)

FIG. 1.

FIG. 3.

FIG. 2.

FIG. 1 is a front elevational view of a holder for golf tees and ball markers showing my new design;

FIG. 2 is a rear elevational view thereof; and

FIG. 3 is a side elevational view.

The broken lines indicating golf tees and markers are for illustrative purposes only.

I claim:

The ornamental design for a holder for golf tees and ball markers, as shown and described.
